UNITED STATES PATENT OFFICE.

JAN BOROWIEC, OF EAST CHICAGO, INDIANA.

WINDOW.

Application filed October 11, 1923. Serial No. 667,917.

To all whom it may concern:

Be it known that I, JAN BOROWIEC, a citizen of Poland, residing at East Chicago, in the county of Lake and State of Indiana, have invented certain new and useful Improvements in Windows, of which the following is a specification.

This invention relates to improvements in windows having vertically sliding sash members.

An important object of the invention is to provide means for permitting the sash members to be swung laterally, inwardly for conveniently positioning the same to aid in cleaning or replacing the glass window panes.

A further object of the invention is to provide novel means for supporting and guiding said sash members while in their operative positions.

A still further object of the invention is to provide novel means for retaining said sash members in their operative positions and for permitting them to be moved into their inoperative or laterally swung positions.

Other objects and advantages of the invention will be apparent during the course of the following description.

In the accompanying drawings forming a part of this specification and in which like numerals are employed to designate like parts throughout the same,

Figure 1 is an elevational view of the inner side of a window frame and sash members embodying this invention.

Figure 2 is a vertical sectional view taken upon line II—II of Fig. 1.

Figure 3 is a horizontal sectional view taken upon line III—III of Fig. 1, showing the window sash members in their operative positions.

Figure 4 is a horizontal transverse sectional view, partly in plan view, showing the sash members in their inoperative or laterally swung positions.

Figure 5 is a fragmentary view partly in elevation and partly in section of the upper right corner of the window frame and upper window sash and shows one of the sash weight wells with the vertically extending inner facing board removed.

Figure 6 is a vertical sectional view, partly in elevation, of the window frame with the lower window sash swung laterally into its inoperative position,

Figure 7 is a fragmentary perspective view of one of the supporting guide strips employed in connection with the sash members,

Figure 8 is a fragmentary perspective view of one corner of a sash member showing the type of hinge members employed for swingingly connecting the sash members to the supporting guide strips,

Figure 9 is a fragmentary perspective view of a portion of a laterally shiftable retainer guide strip shown in section in Figs. 3 and 4,

Figure 10 is a fragmentary transverse sectional view of a sash member and a supporting guide strip with the hinged member employed for connecting the same shown in plan view,

Figure 11 is a fragmentary sectional view, partly in elevation, showing the locking bolts employed for retaining the hingedly mounted finishing strips in their normal operative positions, and

Figure 12 is a detail perspective view of a latch member shown in operation in Figs. 4 and 6.

In the drawings, wherein for the purpose of illustration is shown a preferred embodiment of this invention, the numeral 5 designates the bottom sill board of a window frame which further consists of vertically extending inner facing boards 6 and 7 having connected to their inner longitudinal edges the inner side wall boards 8 and 9 which form a part of the sash weight wells 10, the said wells being further provided with outer side wall boards 11 and 12 which are properly secured to the outer longitudinal edges of the inner facing boards 6 and 7 respectively. It will be seen that these inner side wall boards 8 and 9 are of reduced width with respect to the outer side wall boards 11 and 12 for the purpose of permitting the outer vertical flange members 13 and 14 to be secured to their outer longitudinal edges. Traversing the upper ends of the vertically extending inner face boards 6 and 7 and properly secured thereto is an inner head board 15 which has connected to its lower longitudinal edge upon the rear face of the same the top board 16, best shown in Figs. 2, 5 and 6. There is further provided an outer head board 17 which is positioned exteriorly of the building wall within which this window frame is mounted.

Extending vertically between the sill

board 5 and top board 16 and positioned in proximity to the inner side wall 8 of one of the sash weight wells 10 and the outer vertical flange member 13 is a supporting guide strip 18 which is of semi-tubular formation having a longitudinally extending groove 19 formed therein. Extending longitudinally through this groove 19 and passing through axially arranged openings formed in end pieces which close the ends of the said groove is a pintle member 20 which projects beyond the ends of the supporting guide strip 18 for entering recesses formed in the sill board 5 and top board 16 for the purpose of permitting rotation of the said guide strip. This supporting guide strip 18 is provided with a longitudinally extending bead 21 formed on one side edge of the same which is adapted for slidably engaging the rabbetted edge 22 of the upper window sash 23. In Figs. 8 and 10 there are shown hinge members which are employed for connecting the sash 23 to the pintle 20 carried by the supporting guide strip 18. These hinges consist of plate members 24' which are countersunk into the edge of the window sash and are provided with oppositely extending eye portions 25' and 26' as shown. The eye portion 25' is intended to receive the pintle 20 for being slidably retained within the longitudinally extending groove 19. The eye 26' enters a suitable recess for the purpose of receiving a rod 27' which extends through this portion of the sash. It will be seen by this construction that the window sash 23 will be slidably supported by this guide strip 18. At the opposite side of the window frame in proximity to the sash well wall 9 and outer vertical flange 14 is a vertically extending retainer guide strip 24 which is rotatably supported by means of the longitudinally extending rod 25 which projects at its opposite ends into suitable recesses formed in the sill board 5 and top board 16. This retainer guide strip is provided with a beaded edge 26 that is adapted for slidably engaging the rabbeted edge 27 of the upper window sash 23. The opposite side edge of the retainer guide strip 24 is provided with a small lug 27a which is intended to engage the outer face of the window sash for retaining the same in sliding engagement with the guide strip.

Positioned adjacent the retainer guide strip 24 and extending in parallelism with the same is a supporting guide strip 28 which is of very similar construction to the supporting guide strip 18. This guide strip 28 is shown in detail in Fig. 7 which illustrates the fact that it is of semi-tubular formation. The pintle 29 extends longitudinally through the groove 30 formed in the said strip and projects beyond the end pieces 31 for being received in recesses formed in the sill board 5 and top board 16. It will

be noted that this guide strip differs from the guide strip 18 only in that it is not provided with a longitudinally extending bead on one edge of the same. The lower window sash 32 is slidably connected to the supporting guide strip 28 in the same manner described in connection with the Figs. 8 and 10.

By inspecting Fig. 4, it will be seen that when the retainer guide strip 24 is rotated upon its supporting rod 25, the bead 26 will be moved out of engagement with the rabbeted edge 27 of the upper window sash 23. This will permit the said sash to be swung laterally inwardly, due to the fact that it is supported upon the rotatable guide strip 18. There is provided a laterally slidably retainer guide strip 33 flatly engaging the inner side wall 8 of one of the sash weight wells 10. Longitudinally hinged to the front edge of the vertically extending inner facing board 6 is a finishing strip 34 which is connected to the laterally shiftable retainer guiding strip 33 by means of the links 35. It will be seen that when this finishing strip 34 is swung upon its hinges, the retainer guide strip will be shifted laterally for being moved away from the supporting guide strip 18 for the purpose of permitting rotation of the same. By inspecting Fig. 3, it will be seen that when this laterally shiftable retainer guide strip 33 is positioned adjacent the supporting guide strip 18, its inner face acts as a guide for the left hand edge of the lower sash 32. The inner edge of the finishing strip 34 will act as a beading for the left hand edge of this lower sash 32. Hinged to the inner longitudinal edge of the vertically extending inner facing board 7 is a second finishing strip 36 which is intended to be moved into the position shown in Fig. 3 for aiding in retaining the guide strips 24 and 28 in their operative positions for permitting sliding movement of the upper and lower sashes 23 and 32 respectively. The finishing strips 34 and 36 are provided with outwardly sprung pressed bolts 37, shown in detail in Fig. 11, for the purpose of permitting the opposite ends of the same to be connected to the sill board 5 and top board 16 when in their closed or operative positions. This bolt 37 is provided with a knob 38 which extends outwardly through a suitable slot 39 formed in the said strip for the purpose of moving the said bolt entirely within the cavity for the same formed in the strip and thereby disengaging its projecting end from either the sill board or top board 5 or 16 respectively.

By inspecting Figs. 4 and 6, it will be seen that there is provided a recess 40 in the inner side wall 9 of the right hand sash weight well 10 for the purpose of receiving the latch member 41 shown in detail in Fig.

12, which is pivotally supported within the said recess and is adapted to be swung into a horizontally extending position for restricting the movement of the guide strip 5 55 28 for retaining the lower sash 32 in its open or laterally, inwardly swung position.

It is to be understood that the top board 16 is provided with suitable slots 42, shown in detail in Fig. 5, adjacent its opposite 10 ends for the purpose of receiving grooved pulley wheels 43 that are intended for supporting the sash weight ropes 44 which carry the sash weights 45. When the window sashes are swung into their open positions, the sash weight ropes 44, carried by the inwardly swung edges, will extend from the top of the sashes to the slots 42 in the manner illustrated in Fig. 4.

The operation of the window sashes embodying this invention may be described as follows:—

In Fig. 3, the upper and lower window sashes are shown in their operative positions or in positions permitting the same to 25 be vertically moved in the guiding strips associated with their vertical edges. When it is desired to swing the sash members into the positions shown in Fig. 4, the bolts 37 associated with opposite ends of the finishing strips 34 and 36, are moved inwardly 30 against the tension of their springs and the said finishing strips are swung into their open positions, as shown in Fig. 4. The movement of the finishing strip 34 will 35 cause the retainer guide strip 33 to be shifted laterally for causing the same to be moved out of engagement with the supporting guide strip 18. The finishing strip 36 will be moved out of engagement with the supporting guide strip 28. The lower sash 32 40 may be swung into the position shown in Fig. 4. By causing the retainer guide strip 24 to be slightly rotated to cause the same to assume the position shown in Fig. 4, the bead 26 will be moved out of engagement 45 with the rabbeted edge 27 formed on the upper sash 23 and will thereby permit the same to be swung into its open position, as shown. The sash members may be returned 50 to their normal operative position in the reverse manner and the finishing strips 34 and 36 may be returned to their closed or operative position with the bolts 37 received

in the recesses carried by the sill board 5 and top board 16.

It is to be understood that the form of this invention herewith shown and described is to be taken as the preferred example of the same, and that various changes in the shape, size, and arrangement of parts may 60 be resorted to without departing from the spirit of the invention or the scope of the subjoined claims.

Having thus described the invention, I 65 claim:—

1. In a window of the class described, a frame, a sash member in said frame, a supporting and guiding member for one vertical edge of said sash member, means carried by said frame for pivotally carrying 70 the supporting and guiding member, means carried by the sash for slidably connecting it to the last mentioned means, and a movable retaining member for the second vertical edge of the sash member, said movable 75 retaining member being adapted for preventing or permitting lateral swinging movement of said sash member.

2. In a window of the class described, a frame, sash members in said frame, a rotatable supporting member for each sash, a rotatable retaining member for one sash, and a laterally slidably displaceable retaining member for the second sash, said retaining members being adapted for movement 80 to permit said sash members to be swung laterally on their rotatable supports.

3. In a window of the class described, a frame, sash members in said frame, a rotatable semi-tubular supporting guide strip 90 for each sash member, a movable retaining guide strip for each sash member whereby said supporting and retaining guide strips will permit sliding movement of said sash members when in their normal positions 95 and will permit swinging movement of said sash members when the retaining guide strips are moved out of their normal positions, and means associated with said frame and one of said supporting guide strips for holding the sash member carried by the last mentioned guide strip in its laterally swung position.

In testimony whereof I affix my signature.

JAN BOROWIEC.
